(57) **CLAIM**

The ornamental design for a display screen with graphical user interface for fluorescent endotoxin detection, as shown and described.

DESCRIPTION

FIG. 1 is a view of an embodiment of a display screen with graphical user interface for fluorescent endotoxin detection showing our new design; and,

FIG. 2 is a view of an embodiment of a display screen with graphical user interface for fluorescent endotoxin detection showing our new design.

The outermost broken lines in the drawings illustrates a display screen that form no part of the claimed design. The broken line showings of text in the drawings illustrate portions of the graphical user interface that form no part of the claimed design.
